UNITED STATES PATENT OFFICE.

EDMUND F. HARTSHORN, OF NEWARK, NEW JERSEY, ASSIGNOR TO THE STEWART HARTSHORN COMPANY, OF NEW JERSEY.

DESIGN FOR A BRACKET FOR SHADE-ROLLERS.

SPECIFICATION forming part of Design No. 32,530, dated April 17, 1900.

Application filed November 15, 1899. Serial No. 737,131. Term of patent 14 years.

To all whom it may concern:

Be it known that I, EDMUND F. HARTSHORN, a citizen of the United States of America, and a resident of Newark, county of Essex, State 5 of New Jersey, have invented a certain new and original Design for Brackets for Shade-Rollers, of which the following is a specification.

In the accompanying drawing, forming part 10 of this specification, is illustrated a perspective of a bracket member formed according to my invention.

As shown in the drawing, the design of the bracket consists of a broad flat vertical plate 15 *a*, from the edge of which projects a flat arm *b* of substantially the shape and contour shown in the drawing. The bracket at opposite points is formed with a round and an elongated opening. For instance, the elongated

opening *d* is illustrated as formed in the outer 20 end of the arm *b* and the round opening *c* as near the edge of the plate *a*, the essential feature of the design being the vertical plate having the horizontal arm extending from its edge and the two openings arranged opposite 25 to each other on a horizontal line, or substantially so, one of the openings being elongated and the other round, as shown. In the sides of the vertical plate *a* are holes *f*.

What I claim is—

The design for a bracket for shade-rollers as herein shown and described.

Signed by me at Newark, New Jersey, this 21st day of October, A. D. 1899.

EDMUND F. HARTSHORN.
